COLLAPSIBLE TUBE PASTE DISPENSER

Edward J. Ernst, St. Johns, Mich.

Application April 22, 1955, Serial No. 35,633

Term of patent 14 years

(Cl. D52—2)

I claim:

The ornamental design for a collapsible tube paste dispenser, as shown.
